CONTAINER

Bradford W. Brown, Northbrook, Ill., assignor to
 Container Corporation of America, Chicago,
 Ill., a corporation of Delaware

Application March 23, 1936, Serial No. 70,246

4 Claims. (Cl. 229—45)

The present invention relates to containers which are particularly adapted for the packing of ice cream and other edible materials which are intended to be made up in individual packages to be eaten directly from the container.

5 One object of the invention is to provide a relatively liquid-tight container capable of being manufactured in complete form at the box plant so that the container may be set up by the user 10 without requiring any special machinery or without use of fastening devices other than the parts of the container itself.

A further object of the invention is to provide a simple and effective construction of container including retaining means for a cover adapted to engage with parts on the cover to hold the same securely in place when the cover is assembled with the container.

15 A further object is to provide a container of the type above described which will be extremely simple in form and easy to set up and use and which will be effective for the purpose intended.

20 To these and other ends the invention resides in certain improvements and combinations of parts, all as will be hereinafter more fully described, the novel features being pointed out in the claims at the end of the specification.

In the drawings:

25 Fig. 1 is a perspective view of one form of the container set up with the cover in place;

Fig. 2 is a fragmentary detail showing the manner of retaining the cover on the container;

Fig. 3 is a fragmentary perspective view of the parts shown in Fig. 2;

30 Fig. 4 is a view of the blank of the body portion of the container;

Fig. 5 is a view of the closure blank;

Fig. 6 is a perspective view of a modified form of container;

40 Fig. 7 is a fragmentary detail view, similar to Fig. 2, showing the manner of retaining the cover on the container;

Fig. 8 is a view of the blank of the body portion of the container; and

45 Fig. 9 is a view of the closure blank similar to Fig. 5.

The container of the present invention, as herein disclosed, comprises a tapered tray portion or container proper and a cover portion adapted to be retained in place on the container so as to be secure from accidental displacement.

50 Referring more particularly to the drawings, the container proper designated at 1 comprises a bottom 2, side walls 3 and 4 and end walls 5 and 6 which are preferably formed with out-

wardly tapered edges. The side walls 3 and 4 are provided respectively at their ends with flaps 3a, 3b and 4a, 4b. These flaps are formed with conventional interlocking portions which engage with each other to retain the container in assembled or set-up condition, see particularly Fig.

5 1. The end walls 5 and 6 are, in the present instance, first folded inwardly in assembling the container so that they will lie inside of the assembled interlocking flaps 3a, 4a and 3b, 4b. Due 10 to the construction just described it is apparent that the container may be set up and retained in condition to effectively hold the material. Other conventional means could, if desired, be employed to retain the side walls in container 15 forming position.

The cover for the container preferably comprises a closure panel 7 having side extensions 8, 8 and end extensions 9, 9 all defined from the closure panel by the score lines indicated. By 20 folding inwardly the side and end extensions 8, 8, and 9, 9 it will be observed that a recessed closure is formed which will fit within the top of the container 1 with the upper edges of the extension lying substantially flush with the upper edges of the side walls of the container. The extensions are preferably flared toward their outer ends so that when they are bent upwardly the sides of the cover thus formed will substantially conform to the taper of the side walls of 30 the container.

In order to provide means for releasably locking the cover to the container, the blank of the cover is formed to provide a small tongue or projection 10 which is formed by making a slit in 35 each extension 9, 9, the ends of which slit terminate at the score line between the extension and the closure panel 7. This portion 10 is not scored so that when the extensions 9, 9 are bent upwardly the projections 10 will extend outwardly 40 of the cover and will remain in substantially the same plane as the plane of the closure panel 7. When the extensions 9, 9 are thus bent upwardly an opening 11 will be provided in each extension within which can be retained the 45 ends of a spoon, if desired, in the manner shown in my copending application, Serial No. 36,759, filed August 19, 1935.

50 Retaining portions are provided on the container 1, which, in the present instance, are conveniently formed by providing extensions 12, 12 on the walls 5 and 6, which extensions are adapted to be folded inwardly against the inner faces of the side walls 5 and 6 and may, if desired, be secured by means of adhesive. These extensions 55

12, 12 thus form relatively narrow abutment members or retaining strips on the inner faces of the side walls 5 and 6; and the projections 10, 10 on the cover are adapted to snap into place beneath the lower edge of these strips so as to retain the cover in place on the container.

It is to be understood that the overall length of the cover through the projections 10, 10 is substantially equal to the corresponding interior dimension of the container when the cover is in place thereon. Due to this relationship it is apparent that, when the cover is being inserted, the projections 10, 10 bear against the inner faces of the strips 12, 12 and slightly deflect the side walls 5 and 6 outwardly until the projections pass below the strips and snap into engaging relationship with the lower edges thereof. This will allow the side walls to substantially retain their original plane condition in which the extensions 9, 9 on the cover will lie flat against the strips 12, 12 and the extensions 8, 8 on the cover will lie flat against the side walls 3 and 4, thus making a substantially liquid-tight container which is well suited for the packaging of frozen confections, such as ice cream.

Referring to the modified form of the invention illustrated in Figs. 6 to 9, inclusive, the body portion of the container comprises a bottom 22, side walls 23, 24, 25 and 26 and the locking flaps 30 23a, 23b, 24a and 24b. These parts are similar to the corresponding parts illustrated in Figs. 1 to 5. Reinforcing strips 23c and 24c, in this form of the invention, are provided respectively on walls 23 and 24. These strips are designed to be folded inwardly and to be adhesively secured to the inner faces of their attached walls to thus give these walls a greater rigidity along their upper edges than they would otherwise normally have. Extensions 32, 32 are provided on the walls 25 and 26, each of these extensions being somewhat U-shaped to provide additional tab-like extended portions 32a, 32a at the extremities of the extensions 32. The free edge 32c of the central portion of the flaps 32 will perform the same function as the free edge of strip 12 in the form of the invention shown in Figs. 1 to 5, namely, to retain the cover from upward displacement.

The extended portions 32a, 32a serve to reinforce the container adjacent its corners and permit the container to be made from lighter stock than would be required without these portions.

The cover comprises a central panel 27 having side extensions 28, 28 and end extensions 29 and 29, the cover being also formed to include projections 30, 30, all of which features are substantially the same as the features illustrated in Fig. 5.

It is to be noted that the inturned edge portions 23c, 24c together with the inturned flaps 32 together with the portions 32a, 32a thereon very definitely reinforce the construction of the container so that a relatively sturdy container can be formed by considerably lighter board than would be required in the event these reinforcing portions are dispensed with.

In the use of the modified form of the container, the extensions 32, 32 will be folded inwardly against their respective attached walls 25 and 26 and will preferably be secured in place by suitable adhesive. The cover portion of the container will be secured thereto as in the previously described form merely by forcing the cover within the top part of the container so that the

projections 30, 30 on the cover engage beneath the edges 32c, 32c.

From the foregoing description it is apparent that a convenient and effective form of container for edible materials is provided which can be packed flat for shipment to the user and by him readily set up and assembled without requiring special equipment. Due to the use of the in-turned strips under the edges of which the projections on the cover are adapted to interlock, an effective means for retaining the cover is provided without the use of an opening through the side walls. The elimination of such an opening in the side walls prevents the loss of contents and insures maximum cleanliness and freedom from contamination. These features, together with the feature of simplification of construction whereby the cover for the container may be readily assembled and removed, make the present container very desirable from both a sanitary and operations standpoint.

While the present description sets forth a preferred embodiment of the invention, certain changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A container comprising a bottom and four side walls, a recessed cover portion comprising a closure panel having upwardly folded extensions thereon, projecting portions on said cover portion lying in the plane of said closure panel and disposed on two opposite edges thereof and of a length such that the over-all dimension of the cover is substantially equal to the corresponding normal interior dimension of the container, and locking abutments comprising strips of paper-board secured flat against the upper portions of the interior faces of two opposite side walls, the bottom edges of said abutments adapted to be engaged by the projecting portions on the cover to retain the cover in operative position on the container, said upwardly folded extensions lying loosely in unsecured relation against the outer surfaces of said locking abutments.

2. A container comprising a bottom and four side walls, two opposite side walls having extensions thereon adapted to be folded down and secured to the inner faces of said side walls and terminating near the upper edges thereof, a recessed cover portion comprising a closure panel having upwardly folded extensions thereon, projecting portions on said cover portion disposed on two opposite edges thereof, said projecting portions extending beyond the plane of said upwardly folded extensions and being adapted to engage beneath the lateral edges of the inwardly folded extensions on the side walls when the closure is in operative position on the container, said upwardly folded extensions lying against the outer surface of said side wall extensions.

3. A container comprising a bottom and four side walls, an extension on the upper edge of each side wall, the extensions on two opposite side walls having additional tab-like extensions at each end thereof adapted to lie along the corners of the container in its set-up condition, said extensions being secured flat against the inner faces of said side walls and serving to substantially reinforce the container whereby a

board of minimum thickness may be employed in the construction of the container, and a flanged closure for said container having projections on at least two opposed sides thereof, said projections lying in the plane of said closure and engaging beneath the end edges of said extensions on two opposed side walls to hold said closure in place.

4. In a container having a bottom and four side walls and being provided with a closure having upwardly folded flaps thereon, the combination of extensions on the upper edges of two

opposed side walls, said extensions being folded inwardly and secured to their respective side walls, and projecting portions disposed on at least two opposite edges of said closure, said projecting portions lying in the plane of said closure and being adapted to be engaged beneath the bottom edges of said extensions to hold said closure in position, said upwardly folded flaps lying loosely in unsecured position against the outer surface of said extensions. 5 10

BRADFORD W. BROWN.
